6350X

Jonathan Newhall
Sellers Patent.

The Schedule referred to in these Letters Patent and making part of the same containing a description in the words of the said Jonathan Newhall him-
self of his improvement in the Hand-wheel Plane for Planing Boards, ^{timber}, &c.

This machine consists of a wheel three feet in diameter more or less, made of wood or any other suitable material, confined upon the end of a suitable
shaft of inflexible substance and sufficient length to form bearings for
the revolution of the wheel and the application of appendages necessary
to give it motion. The wheel is faced upon the side to the shaft, with
a bevel extending from the edge, some two inches more or less, towards
the centre of the wheel, and about a half inch in depth at the periph-
ery. Plane irons are imbedded in the rim of the wheel near the periph-
ery. Their edges should correspond with the radius of the wheel, &
the shape of the face as levelled. Double Irons may be used to prevent
injury to cross grained wood, or single iron, with good effect
by means of metal plates, made as to ride over the iron, and about three
inches in length. They should be imbedded before the edge of the plane
iron, so as to agree with the face and form the mouth of the iron, being
confined upon the rim of the wheel by a screw so constructed that the
plate may slide in its bed to open or shut the mouth more or less at
pleasure. (a close mouth answering the purpose of a double iron)
To plane timber and boards, the wheel is placed in a vertical position,
and for planing boards, a carriage is made of sufficient width and
length to receive the board and made to traverse upon a rail par-
allel with the face of the wheel, being held by a tongue and groove
at the upper edge to sustain its position, and worked by a rack and
pinion at the lower edge by hand or otherwise at pleasure. The board
is laid upon the carriage and held in place by a spring roller and
suitable dogs. The wheel resting on suitable guides or blocks is made
to slide in a horizontal direction towards the carriage, or from it
agreeable to any thickness to be planed. By means of a sliding Rail

Drawing

filled to the shape so as to carry the wheel along with it. A lever or screw is attached to the Box, and thereby brought to bear on the wheel, to give it the position required. To plane joint a carriage is made of timber of suitable length, thickness, and width to receive the joint which is laid upon it with the side to be planed projecting towards the wheel over the edge of the carriage as much as is to be planed off, and held down by dogs at each end of the same, formed for the purpose. The carriage for joint and timber should run on two rails near its under edges, and may be worked by a rack and pinion or otherwise at pleasure. A horizontal position of the wheel is recommended when boards or planks only are to be planed. The frame may be made according to circumstances, and any convenient power may be applied. The principles which I claim as new and being my invention are

1st The Bevel on the face of the wheel, the use of which is to admit the lumber to enter between the carriage and the edge of the wheel and thereby presenting the part to be planed off to the action of the planes. — 2nd The sliding motion of the wheel, by which various thicknesses may be planed. 3rd The running timber by the carriage as in the above description of planing boards.

4th The metallic plate, the use of which is to answer the purpose of double irons, which principle is contemplated to be applied to hand planes. In testimony that the foregoing is a true specification of the invention, herein described and of the mode of using the same I have hereunto set my hand and seal at Washington in the County of Lincoln and State of Maine this fourth day of January in the year of our Lord one thousand eight hundred and thirty one.

End.
